UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR A LOOP FOR LIGHTING FIXTURES.

Application filed April 13, 1927. Serial No. 21,587. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for a Loop for Lighting Fixtures, of which the following is a specification, reference being had to the accompanying drawing, forming part thereof.

Figure 1 is a front view of a loop for lighting fixtures, showing my new design.

Figure 2 is a bottom plan view of a loop for lighting fixtures, showing my new design.

I claim:

The ornamental design for a loop for lighting fixtures, as shown.

JOHN A. BOEHRINGER.
